TORCH OR LAMP

Robert A. Currie, Syracuse, N. Y., assignor to R. E. Dietz Company, New York, N. Y.

Application January 9, 1936, Serial No. 58,353

8 Claims. (Cl. 67—55)

This invention relates to improvements in torches, flares or lamps of that sort, ordinarily used out of doors as signals and for other purposes, in which the flame is exposed or flares out from the burner unconfined by the glass chimney or enclosure commonly used in lanterns and lamps. Among the uses of such torches or flares, it may be mentioned that they are used as warning or danger signals on construction jobs, and 5 are carried by trucks or vehicles for use in emergencies as danger signals on highways.

Since it is important to protect the flames or burners of such torches in a way to prevent or lessen the danger of the flames being extinguished by winds and rain, the torch burners are 15 ordinarily formed or furnished with metal guards providing openings through which the flames issue or flare out, but which afford more or less protection against the elements, so that the 20 torches will not be extinguished in use under weather conditions commonly encountered.

It has been found in the use of such torches that soot or carbon is formed and accumulates to an objectionable extent in or about the burner or flame guard, and in some previous constructions the soot assumes what might be called "mushroom proportions" and fills or clogs the flame exit openings or air admission openings of the burner guards or covers so as to seriously affect their operation and reduce their lighting 25 efficiency.

One purpose of my invention is to improve torches of the type mentioned so as to increase their efficiency and reliability of operation, particularly when used under severe weather 30 conditions.

Other objects of the invention are to provide a torch of improved construction which will insure more perfect combustion and an increased 35 candle power of the light while, nevertheless, the burner and flame are effectually protected from the elements and prevented from being extinguished by wind, rain or snow, even under severe storm conditions; in which the burner laterally 40 confines or supports the outer or flame end of the wick so as to retain its shape and prevent it from spreading out in the flame guard or protector and thereby prevent or greatly reduce the objectionable formation or accumulation of soot or 45 carbon; in which the wick tube laterally confines or supports the upper end of the wick and provides lateral openings through which the flame issues or flares in a manner to better the feed of the oil and cause it to burn more freely and produce 50 a brighter flame; in which a shield or guard sur-

rounding the upper portion of the wick tube or burner effectively protects the flame from being extinguished by strong winds, and a shield or guard above the burner and windshield protects the wick and burner from rain; and which has 5 the other features of advantage and improvement hereinafter described and set forth in the claims.

In the accompanying drawing:

Fig. 1 is a side elevation, partly in section, of a torch of a construction embodying my invention, showing the removable protecting cover or cap in place over the burner.

Fig. 2 is a side elevation, enlarged, of the burner detached.

Fig. 3 is a sectional elevation, enlarged, of the 15 upper portion of the torch.

Fig. 4 is a detail elevation of the wick tube.

Fig. 5 is a sectional plan view of the burner on line 5—5, Fig. 2.

Fig. 6 is an enlarged detail section showing the 20 leak-tight joint between the removable protecting cover and the body of the torch.

The body or oil fount of the torch may be of any usual or suitable form and construction. As shown, it consists of a metal fuel receptacle provided at its top with an upwardly projecting, reduced portion or neck 11 formed with a central opening 12 for the reception of the wick tube 13 of the burner through which the wick 13a passes.

Preferably, the wick tube 13 is substantially 30 cylindrical and extends through and is removably secured in the central opening 12 of the neck by a collar which has a cylindrical flange 14 that surrounds and is brazed or otherwise fixed on the wick tube, and a laterally projecting circular 35 flange 15 provided at its outer edge with lugs 16 adapted to releasably engage fixed complementary locking lugs 17 on the neck of the fount for removably retaining the wick tube in place. Either the lugs 16 or 17, or both, may be inclined 40 or cammed so as to wedge the wick tube inwardly or downwardly by a partial rotation thereof. As shown, the locking lugs 17 are provided on a screw threaded ring 18 which is screwed or otherwise stationarily secured on the neck 11, and has 45 the locking lugs projecting inwardly from its inner periphery over a sealing gasket or washer 19 seated in a central depression in the outer end of the neck. When the lugs 16 of the collar are forced under the locking lugs 17 by a partial rotation of the wick tube, the lateral flange of the collar will be wedged or forced down against the sealing washer and form an oil-tight joint.

The upper or outer portion of the wick tube is formed with openings 20 in its side walls through 55

which the flame issues or burns, these openings, as shown, being formed by slotting the upper portion of the wick tube to form spaced upright wall portions or posts 21, the spaces between which 5 form the flame-exit openings. As shown, these posts 21 taper upwardly and flare or diverge somewhat outwardly and upwardly from their lower portions, and the posts 21 form supports for a rain shield 22 which is located over the slotted 10 upper end portion of the wick tube. Preferably, this shield is circular and of shallow arched or dome shape and is provided with circumferential slits, and the portions 23 of the shield, between its center and said slits, are punched out 15 or offset upwardly so as to form openings 24 in the shield beneath the outer edges of said offset portions. These openings 24 are of substantial vertical height but very narrow radially, so that while they provide passages through the shield 20 through which the flame can burn, and smoke or gases can escape, the offset portions 23 form roofs or guards for the openings to prevent appreciable entrance of rain therethrough. The rain shield is of sufficient diameter to project out laterally 25 beyond the sides of the wick tube far enough to effectually prevent driving rain from entering the side openings of the wick tube and wetting the wick or extinguishing the flame. As shown, the upper ends of the posts 21 are bent laterally outward 30 and are secured to the rain shield, as by welding, so as to securely support and hold the rain shield.

Surrounding the wick tube or burner below the rain shield, is an open-topped annular windshield 35 or guard. As shown, this has a cylindrical wall 25 which surrounds and is spaced from the wick tube, and a bottom wall 26 which extends inwardly from the lower end of the cylindrical wall to the wick tube and has a downwardly projecting flange which fits around and is welded or otherwise fixed to the wick tube so as to secure the windshield to the wick tube or burner. The space formed between the cylindrical wall 25 of the windshield and the wick tube or burner is open 45 at its upper end so that the flame can issue unimpeded through the uninterrupted space between the upper edge of the windshield and the rain shield. Preferably, the rain shield is of larger diameter than and projects out beyond the cylindrical windshield to better prevent rain from entering through the space between the shields. 50 The windshield is provided with suitable openings for the admission of the necessary air to the burner, it being, as shown, provided with small spaced openings 28 in its side walls and with small perforations 29 in its bottom wall. These perforations 29 are preferably formed with upstanding rims and serve as drain openings for the escape of water from the windshield. While the 55 raised rims form a shallow trap which normally prevents oil, that may seep out of the wick tube into the windshield, from running out on to the body of the torch, they prevent accumulation of oil or water in the windshield to a depth to interfere with the proper operation of the torch. The windshield is preferably disposed with reference to the wick tube or burner so that the upper edge of the windshield is located at an elevation above the lower ends of the side openings 20 in 60 the wick tube while the air admission openings 28 of the windshield are disposed at an elevation somewhat below the bottom ends of the side openings 20 of the wick tube.

In the use of the torch, the wick is adjusted 75 so that its upper or exposed end will be located

about at or somewhat above the bottoms of the side openings 20 of the wick tube. Thus, the upper end of the wick will be confined or prevented from unduly spreading laterally or protruding from the wick tube by the posts or portions of the wick tube between the side openings thereof through which the flame issues. This 5 holds the wick to shape and reduces to a great extent formation and accumulation of soot or carbon on or about the burner, which naturally has 10 a bad effect on the flame, cutting off the air supply and clogging the openings through which the flame is supposed to escape. The wick confined in the wick tube with the side openings gives 15 with a brighter flame generating more gas from the exposed side portions of the wick.

For properly supporting the wick in the wick tube and permitting the ready adjustment thereof so as to locate the upper end of the wick at a 20 correct height or level with reference to the flame openings 20, the wick tube is preferably provided at its lower end with an inturned or indent spiral or helical lip 30. This lip, which extends part-way around the periphery of the wick 25 tube, with its ends separated by a plain or unlined gap 31, acts as a screwthread pressing into the wick, so that by turning the wick in one or the other direction in the wick tube, it will be moved upwardly or downwardly in the tube, and 30 the lip will support the wick in the position to which it is adjusted. Thus, the wick can be readily adjusted to the desired height simply by turning it in the appropriate direction in the wick tube. 35

32 indicates a removable cover or cap adapted to be secured on the torch over the burner and shields with an oil-tight joint which prevents escape of oil from the torch. This cover is particularly desirable for torches or flares carried by 40 trucks or vehicles for emergency use. It prevents leakage and waste of oil which otherwise may occur from the shaking or movement of the torch due to the motion of the vehicle or handling, and keeps the torch clean and dry, as well as protecting the burner and shields from injury by striking an object. The cap shown, see Fig. 6, has an out-turned bottom flange 33 on the under face of which a sealing gasket 34 is secured, as by the in-turned edge of the flange. The cap is threaded 50 and adapted to be screwed on the neck of the torch so as to force the gasket tightly against a raised circular bead 35, Fig. 6, on the top of the fount, and surrounding the neck, and thus form an oil-tight joint around the neck and burner. 55

I claim as my invention:

1. A torch comprising a fuel receptacle, a wick tube projecting out from the receptacle and having lateral flame exit openings in the sides of its outer projecting portion, a wick in the wick 60 tube and entering the fuel receptacle and having its outer end terminating in the wick tube adjacent the inner ends of said exit openings so that the wick flame burns through said openings beyond the wick, a windshield surrounding the outer 65 portion of the wick tube, and a rain shield over the outer end of the wick tube above said flame exit openings, said wind and rain shields defining a chamber around said projecting portion of the wick tube and providing a lateral flame exit from 70 said chamber.

2. A torch comprising a fuel receptacle, a wick tube projecting out from the receptacle and having lateral flame exit openings in the sides of its outer projecting portion, a wick extending from 75

the fuel receptacle into the wick tube and terminating at its outer end in the wick tube adjacent the inner ends of said flame exit openings whereby the wick flame burns through said exit openings beyond the wick and the outer end of the wick is confined laterally by the portions of the wick tube between said flame exit openings thereof, a windshield surrounding the outer portion of the wick tube, and a rain shield over the outer 5 end of the wick tube above said flame exit openings, and spaced from the windshield by a lateral flame exit opening.

3. A torch comprising a fuel receptacle, a wick tube projecting out from the receptacle and having lateral flame exit openings in the sides of its outer projecting portion, a wick in the wick tube and entering the fuel receptacle and having its outer end terminating in the wick tube adjacent the inner ends of said exit openings so that the 10 wick flame burns through said openings beyond the wick, a windshield surrounding the portion of the wick tube having said flame exit openings and being open at its outer end which is located below the outer ends of said wick tube openings, and a rain shield supported by the wick tube over the outer end thereof and spaced from said 15 windshield.

4. A torch comprising a fuel receptacle, a wick tube projecting up from the receptacle and having lateral flame exit openings in the sides of its upper projecting portion, a wick extending from the fuel receptacle into the wick tube and having its outer end terminating in the wick tube adjacent the inner ends of said exit openings so that the wick flame burns through said openings beyond the wick, a rain shield supported by the wick tube over the upper end thereof above said flame exit openings, and a windshield surrounding the projecting portion of the wick tube below 20 said rain shield, a flame exit opening being provided at the side of the windshield below the rain shield.

5. A torch comprising a fuel receptacle, a wick tube projecting up from the receptacle and having an upwardly flaring upper portion having lateral flame exit openings in the sides thereof, a wick extending from the fuel receptacle into the wick tube and having its outer end terminat- 25

ing in the wick tube adjacent the inner ends of said exit openings so that the wick flame burns through said openings beyond the wick, a rain shield supported by the upper end of the wick tube over the same above said flame exit openings, and a windshield surrounding the wick tube below and separated from said rain shield by a space through which the flame issues. 30

6. A torch comprising a fuel receptacle, a wick tube projecting up from the receptacle and having lateral flame exit openings in the sides of its upper projecting portion, a wick extending from the fuel receptacle into the wick tube, a rain shield supported by the upper end of the wick tube over the same above said flame exit openings, and a windshield supported by and surrounding the wick tube and having an open upper end spaced downwardly from said rain shield. 35

7. A torch comprising a fuel receptacle, a wick tube projecting out from the receptacle and having an outwardly flaring outer projecting portion provided with lateral flame exit openings in its sides, a wick extending from the fuel receptacle into the wick tube and terminating at its outer end in the wick tube adjacent the inner 40 ends of said flame exit openings whereby the wick flame burns through said exit openings beyond the wick and the outer end of the wick is confined laterally by the portions of the wick tube between said flame exit openings, a windshield surrounding the outer portion of the wick tube, and a rain shield over the outer end of the wick tube above said flame exit openings and above said windshield. 45

8. A torch comprising a fuel receptacle having an externally screw-threaded neck, a wick tube and burner removably secured on said neck by a connection located within the area defined by said external screw thread of the neck and comprising a packing for sealing the joint between the burner and the receptacle, a cap enclosing said burner in the operative position thereof and screwed on said neck, and a gasket-sealed liquid-tight joint formed between said cap and the receptacle surrounding the burner, wick tube and said burner connection. 50

ROBERT A. CURRIE.
